2,663,226

FOLDING SPADE FOR GUN CARRIAGES

Richard E. Meyer, Falls Church, Va., and Orie L. Beardsley, Washington, D. C., assignors to the United States of America as represented by the Secretary of the Army

Application May 17, 1951, Serial No. 226,922

4 Claims. (Cl. 89—40)

(Granted under Title 35, U. S. Code (1952),
sec. 266)

1

The invention described in the specification and claims may be manufactured and used by or for the Government for governmental purposes without the payment to us of any royalty thereon.

The present invention relates generally to emplacing members such as outriggers or trails for gun carriages and mounts.

In the development of modern field ordnance, and as a result of improved methods of fire control for guns used in firing at high speed targets on the ground and in the air, the need for emplacements or trails to give greater stability to the gun carriage has become paramount. Single trails, and divergent or split trails are almost universally used to orient the gun carriage in a fixed position with respect to the ground when the gun is in firing position, so that a major portion of the recoil is transmitted by the trail to the ground where it is subsequently absorbed. By this means greater accuracy of fire is obtained because of decreased mobility of the gun in firing.

When the gun is not in firing position, as for example, when it is being moved, the trail is raised from the ground, and if split trails are used, means are generally provided to lock the trails together, and some means such as a lunette or loop is attached to one of the trail ends so that the gun may be hitched to a prime mover to facilitate movement from place to place.

Generally prior art devices comprise a spade member made integral with the rear end of the trail and disposed to extend below the trail so that it may intrude into the ground when the gun is in firing position. A cavity or ditch sufficiently large to accommodate the spade is dug, the spade member is then placed in the cavity and dirt is piled around it to provide a sturdy emplacement for the gun. However, when a sudden march order is given and the need for quickly moving the gun becomes imperative, the spades must be dug out and much useful time is lost in this operation at a time when such a delay may mean the loss of the gun. Also, when the gun is being towed by a prime mover, since the spade is made integral with the trail, and is so secured to the trail to extend below it in a fixed position, insufficient clearance is provided between the spade point and the surface of the ground with the result that obstacles such as large stones, tree stumps and other impediments encountered on the march, may cause the gun to overturn.

The present invention, developed with the

view of eliminating the defects noted in the prior art devices, is drawn generally to a novel means for assembling a trail and spade device.

Specifically, the invention comprises a trail with pivotal means mounted upon the trail for revolving the spade thereabout from a first or firing position, to a second folded position when the gun carriage is being towed in order to prevent the spade from encountering obstructions which may lie on the ground in the path of the gun carriage.

More specifically there is disclosed a trail, a spade pivotally mounted on said trail so that said spade may be revolved from a first firing position to a second stowed position, primary latching means to lock the spade in either desired position, and second latching means for securing the first latch so that the folding spade may remain locked in first firing position, or in second folded position.

Additionally the invention comprises a second smaller or rock spade which is made integral with the trail and which may be used on extremely hard ground or in rocky areas where the use of the folding spade would not be practicable.

A preferred embodiment of the invention is illustrated in the accompanying drawings wherein:

Fig. 1 is a plan view of the rear section of the trail showing the latch mechanisms, folding spade and floater or bearing plate.

Fig. 2 is an isometric view of the folding spade and spade latching mechanism in firing position.

Fig. 3 is an elevation of the folding spade looking toward the right in Fig. 2.

Fig. 4 is a side elevation of Fig. 1 showing the rock spade, the folding spade in stowed position (solid lines), the folding spade in firing position (dotted lines), and the latch mechanism.

Fig. 5 is a detail view of the secondary latch or bolt mechanism for securing the first latch mechanism.

Fig. 6 is a detail showing castings welded to the trail and formed to accommodate bearing members for the folding spade shaft, and the shaft for the latching mechanism.

Referring to the drawings wherein the same numeral is used to designate like parts in the various views, the gun carriage comprises trail 1 composed of a top plate and two side plates welded together and properly reinforced to form an emplacing member or outrigger. A trail end casting, a portion of which is looped to form lunette 2 is appropriately attached by any convenient means to the trail, whereby the gun car-

age may be hitched to a prime mover when the gun is being towed. A folding spade 3, integrally embossed to form bearings 4 is mounted for rotation about a horizontal axis coincident with shaft 6. Shaft 6 is journaled in spade bearing 4, and in a bearing 5 formed in casting 22 which is welded to a hollowed out portion of the trail. The lower segment of casting 22 comprises rock spade 23. (See Fig. 6.) Nut 7, lock washer 7a and cotter pin 8 fitted on the extreme ends of shaft 6, hold this assembly together. Suitable means (not shown) are provided for occasionally lubricating bearings 4 and shaft 6.

Folding spade 3 has channeled out portions 11 the upper surface forward of its axis of rotation, wherein wear plates 10 are fitted to provide bearing surface for use which will be explained later. Also provided, for a use later to be described, are pins or bosses 9 extending outward 15 a short distance from the outside plates forming the sides of the folding spade, and at a position just forward of the center of the side plates when the spade is in stowed position (see Fig. 10). Stops 11 are also provided on the rearward 20 inclined surface of the folding spade to bear against the bottom plate of trail 1 when the spade is in firing position to act as detents to assist the folding spade locking means, later to be described, to maintain a fixed firing position.

Folding spade 3 is locked in either stowed position, when the gun carriage is being towed, or in firing position by latching mechanism 12 now to be described. This latching mechanism comprises two side members 12a and a latch handle 13 which is made from a flat strip of metal bent to form a U. The side members 12 are triangular in shape with the apex rounded off and the lower surface or base curved. The upper inner surface or apex portion of triangular members 12a are embossed to accommodate a shaft 14, and the ends of the U which form handle 13 are welded to the boss portions of the side members so that by gripping bar 13a which protrudes from the rounded portion of handle 13, the entire latch mechanism including handle 13 and latch side members 12a may be pivoted as a unit about shaft 14. Shaft 14 is journaled in bearings 15 set in castings 15a which is welded to the upper plate of trail 1 (see Fig. 6). Slots or notches 16 are formed in side members 12a to accommodate pins 9 when the folding spade is rotated to stowed position.

The operation of the apparatus thus far described is as follows. Referring to Fig. 4, the folding spade in stowed position is delineated by solid lines. Pins 9 on the folding spade are disposed in slots 16 and serve to maintain the spade in stowed position while the gun carriage is being towed. When it is desired to place the gun in firing position, the ground is prepared by digging a ditch for the folding spade. The bar on handle 13 is gripped and the latching mechanism is rotated clockwise about shaft 14 until pins 9 are released from slots 16 whereupon the folding spade is released to rotate counterclockwise about shaft 6 until the spade is in firing position. Stops 11 bear against the bottom of trail 1 and the curved bottom portions of side members 12a are slid onto the wear plates fitted into the top surface of the folding spade to bear upon wear plates 10. At this time, of course, the emplacing members are lying upon the ground and floaters 21 extending sidewardly in a plane substantially in horizontal alignment with the bottom of the trail,

rearwardly of the folding spade, provides a greater bearing surface for the trail. Dirt is then piled around the spade to hold the entire gun carriage firmly in firing position.

In order to retain the spade and latching mechanism in firing position, or in stowed position when the gun is being towed, additional or secondary latching means are provided as clearly shown in Fig. 5. This latching mechanism is located within and adjacent the flat metal U-strip forming handle 13 and comprises a cylinder 17 and a bolt 18 slideable within said cylinder. A spring 19 biases the bolt forwardly so that its forward end rests on an extension 13b of handle 13 to maintain said handle and consequently the entire latching mechanism in locked position. When it is desired to release the latching mechanism to rotate the folding spade into either stowed or firing position, cam 20 secured to the rearmost 25 end of bolt member 18 is caused to turn clockwise by exerting pressure in a clockwise direction on cam finger 20a. This causes bolt 18 to slide rearwardly in cylinder 17 against the bias of spring 19 until the forward end of the bolt is free of the extension on handle 13 whereupon the latching mechanism is free to be rotated to unlatch the folding spade so that it may be placed in its desired position. As soon as pressure is removed from cam finger 20a, spring 19 forces the bolt forwardly to lock the folding spade in either stowed or in firing position when the handle is in its lowered position.

From the foregoing, taken in connection with the accompanying drawings it is apparent that disclosed emplacing member with its novel folding spade is superior to prior art devices, since by the simple expedient of releasing the spade latching mechanism, and hitching the gun carriage to the prime mover the folding spade may be removed speedily and with facility from the ground without the need for digging it out. Also in towing, the clearance between the spade and the ground is greater than in prior art devices and lessens the chance of having the gun carriage run afoul of obstructions lying on the ground. 45 In addition the rock spade may be used where the condition of the ground is such as to render use of the folding spade impracticable.

Although the improved folding spade has been disclosed in conjunction with a single trail gun carriage, the improvement may also be applied to divergent or split trail gun carriages. Numerous other modifications and alterations of the disclosed structure will be apparent to one skilled in the art and it is obvious that the same may be made without departing from the spirit and scope of the invention as defined in the claims.

We claim:

1. In a gun mount, an emplacing member extending rearwardly of said gun mount, a folding spade pivotally mounted upon said emplacing member and rotatable in counterclockwise direction from a first stowed position to a second firing position and latching means, pivotally mounted upon said emplacing member for rotation about an axis parallel to and located forwardly of said folding spade, adapted to engage said spade and to lock said spade in either relative position.

2. A gun carriage comprising a rearwardly extending emplacing member, a folding spade pivotally mounted on said emplacing member and rotatable from a first stowed position to a second firing position, a latch mounted on said emplacing member for rotation about an axis located forwardly of the axis of rotation of said folding

spade, said latch having a slot for engaging a pin protruding from said folding spade to maintain said spade in stowed position, a handle secured to said latch, a cylinder mounted on said emplacing member and having a bolt slidable to engage and lock said handle, cam and lever means secured to said bolt and actuatable to retract said bolt to disengage said handle whereby said latch may be rotated clockwise to release said folding spade for movement into firing position.

3. In a mobile gun carriage, an elongated trail, a spade, means mounting said spade trail for pivotal counterclockwise movement about an axis fixed transversely of said trail from a first position folded against said trail, to a second downward emplaced position, a latch mounted on said trail or an axis parallel to and located forwardly of said spade axis for pivotal movement from a first, spade-locking position, to a second, spade-releasing position, a pin fixed on said spade, an

5
5
5

abutment surface on said spade, said latch w in first position engaging said pin when spade is in folded position or said surface w said spade is in emplaced position to lock spade in folded or emplacement positions, respectively.

4. A carriage as recited in claim 3 and means releasably locking said latch in first position.
